HAROLD A. DENMIRE, OF AKRON, OHIO, ASSIGNOR TO THE GENERAL TIRE & RUBBER COMPANY, OF AKRON, OHIO, A CORPORATION OF OHIO

PROCESS AND APPARATUS FOR THE MANUFACTURE OF PNEUMATIC TIRES

Application filed May 6, 1926. Serial No. 107,973.

This invention has for its object the improvement in the method and apparatus for the manufacture of pneumatic automobile tires, by which the shaping of the rubberized fabric about the core is performed more easily and efficiently than in the spinning operations which are used almost exclusively at the present time. The invention is particularly useful in the manufacture of tires from the usual 10 cord fabric, and is especially desirable in the construction of tires of large cross-section and small internal diameter.

In the process of spinning as now used in almost all building of tires upon cores, the 15 core is rotated at a high rate of speed and stitchers or spinning rollers are pressed against the sides of the tire and advanced radially from the tread region to the head of the tire, smoothing and applying the loose 20 folds or skirts of the fabric to the sides of the core. The shaping of the fabric about a core requires condensing or circumferential shortening of the fabric. In the manufacture of smaller tires in which the fullness 25 of the fabric is not great, this method operates fairly satisfactorily, although wrinkling will oftentimes occur at the beads of the tire. In the larger sizes of tires, however, the spinning operation is not so successful and it 30 is necessary in certain sizes to dispense with the machine operations entirely and to revert to the old hand methods, as the spinning operations as practiced do not secure the condensation of fabric and absorption of the 35 fullness as required.

In the old spinning process the core is rotated and the spinning rollers are pressed against the fabric so that the free and unapplied skirts of the fabric, or that portion 40 which approaches the spinning rollers, is retarded to a certain extent by the rollers. There is, therefore, a wave of fabric which is built up in front of the stitcher, and if the amount of fullness to be absorbed is great, 45 this fullness will gradually increase until it is relieved by the formation of a wrinkle or fold over which the spinning roller will jump. The wrinkles or folds become larger and more numerous as the fullness increases toward the 50 bead of the tire. Each wrinkle or fold must

be pinched out by hand by the operator in order to obtain a perfect tire.

The process and apparatus of this invention operate upon entirely different principles than the old spinning operation and 55 secure a positive condensation or crowding together of the cords or elements of the fabric so that the fullness is absorbed in the shaping of the fabric about the core. The cords of the fabric are also laid about the core in a 60 more satisfactory manner than is obtainable with the prior method.

As a result, tire building is more easily and correctly accomplished and no hand work is 65 required in the shaping of the fabric about the core.

In the drawings there is shown one form of apparatus embodying the invention and adapted to carry out the process herein disclosed, it being understood that other types 70 of apparatus may be devised for accomplishing the new and improved results, which are intended to be covered herein.

In the drawings:

Figure 1 is a plan view of a tire making machine constructed in accordance with the principles of the invention;

Fig. 2 is a side view;

Fig. 3 is a section through the central plane of the stitchers;

Fig. 4 is a vertical section on the line 4-4 of Fig. 3; and

Fig. 5 is an enlarged section which is intended to illustrate the manner in which the cords are compacted by the stitcher wheels.

Briefly stated, the new principles upon which my invention operates are as follows.

Instead of rotating the core by power applied to its axis, as in former practices, the core is mounted so that it is substantially freely rotatable upon its axis during the stitching operation, it being desirable, in some instances, however, to apply slight retarding action to the rotation of the core in order to obtain the most desirable degree of crowding together and compacting of the cords by the action of the stitcher disc. Although it has been proposed in certain patents to drive the spinning rollers by separate power, as far as known to me this has never gone into com- 95

mercial use and the spinning rollers have been freely rotatable and driven by the core in all commercial embodiments of tire building machines. By the present method, the spinning rollers are positively driven and, by their rotation, the core is driven in turn, the spinning rollers being forced into driving relation to the core and driving the core through the fabric. In this way, a slight differential speed of travel is obtained between the working face of the stitchers and the applied fabric that acts to compact and crowd the elements of the fabric together, the speed of travel of the working face of the stitcher being 10 slightly greater than the speed of travel of the engaged face of the fabric being applied to the core. As the spinning rollers are advanced radially of the core, the pull of the rollers upon the fabric, operating against the 20 drag of the core, pulls or crowds the cords together, thus condensing the fabric circumferentially and taking up the fullness in the loose unapplied skirts.

It will be seen, from the explanation which 25 has been given and from the description of the tire building machine, that as each group or body of unapplied fabric passes between the edge of the power driven spinning roller and the core, the pull on the core exerted 30 through the fabric will cause each cord to shift or be crowded next to its neighboring cord, thus contracting the skirts of the fabric and securing the desired condensation which is necessary to take up the fullness in the 35 unapplied skirt. As the cords pass beneath the spinning roller, they are adhesively secured in position against the side of the core, or the underlying layer of fabric, and the fabric is smoothly and evenly applied without wrinkles and with a complete elimination 40 of the usual puckering or wrinkling.

It will also be observed that, as the fabric approaches the bead line of the core, the relative fullness increases. With the prior method 45 of shaping the fabric about the core, there is no provision made for compensating for this additional fullness. With the present method, the resistance to the driving of the core, and therefore the pull of the stitchers, increases as the stitchers approach the bead due to the fact that the core is being driven from a constantly decreasing radius. As a 50 result, the compacting force exerted by the stitchers increases as it is required to take care of the additional fullness of material. Since the spinning rollers are preferably driven at substantially uniform speed during the stitching operation, the speed of the core increases as the stitchers approach the bead 55 by reason of the decreasing radius from which the core is driven. The centrifugal action resulting from the increased speed of rotation of the core and the progressively increasing fullness of the unattached skirt 60 cause the loose skirt of fabric to more closely

hug the stitching rollers and a progressively greater zone of fabric is acted upon by the stitcher as it approaches the bead, which results in more desirable distribution of tension on the cords of the fabric over the side walls 70 of the tire carcass.

In order to accomplish the results sought for, the usual metallic stitcher or spinning roller may be used. More efficient results are obtained, however, by the use of spinning rollers having softer or yielding working edges, as the flexibility of the stitchers enables a better grip to be obtained upon the fabric, with a more effective crowding or condensing of the cords. 75 80

The process is especially adaptable for the manufacture of cord tires, as the fact that the cords are free from one another, having no substantial cross weave, enables the crowding action to take place more easily 85 and effectively than with the older type of woven fabric formerly used in the manufacture of tires. It is believed, however, that the advantages arising from the manufacture of 90 cord tires would be obtained, although to a lesser extent, in the manufacture of "fabric" tires, as they are known in the art. 95

A form of machine which is constructed and designed to carry out the process which has been described, is illustrated in the drawings, in which the numeral 1 indicates the base or framework of a tire building machine and 2 the core thereof which is supported on the outer end of the core shaft 3. The core shaft has mechanism associated therewith for driving the core at speeds suitable to the application of fabric to the core 2 and for facilitating other conventional operations. The core shaft is mounted so that it may be disengaged from the driving mechanism 100 after it is given a preliminary rotation or spin so as to avoid excessive friction between the core and the stitcher discs when the stitchers are brought into operation. The drive mechanism for the shaft should be disconnected 105 before the stitchers are brought into action. Suitable mechanism, such as an adjustable friction shoe 4, may also be provided for imparting any desired degree of drag to the rotation of the core to insure proper compacting and crowding together of the elements of the 110 fabric being applied thereto. 115

A layer of cord fabric is indicated at 5, the enlarged section in Figure 5 showing the individual cords 6 which are coated and surrounded by the layer of rubber 7 as is customary in the manufacture of tires. 120

At the side of the machine is located the support 10 for the stitching mechanism, which support is arranged to be swung upon the pivot 11 toward or away from stitching position. 125

Upon the support 10 is slidably mounted the stitcher carriage 14 which is fed toward or from the machine by a feed screw 15 oper- 130

ated by a hand wheel 16. The carriage 14 has mounted thereon a pair of brackets 17 which are pivoted on vertical posts 18 secured in the carriage 14. A headed guiding pin 20 moves in the slot 21 on the upper surface of the carriage and guides each bracket in its oscillatory movement.

Each bracket is formed with upstanding arms 25 in which is mounted the spinning 10 roller shaft 26, the outer end of which carries the spinning or stitching roller 27. Each spinning roller is provided with a soft or yielding working edge or surface 28, which is preferably formed of leather, although 15 wood fibre with a knurled or smooth working face or other yielding substances may be employed. The working edge is secured in place by a ring-shaped plate 30 attached to the face of the stitcher.

20 The two shafts 26 are connected together for simultaneous rotation by a pair of meshing gears 32 which are located above the pivots 18 and are crowned so as to remain in mesh during the pivotal movement of the 25 stitcher brackets. The ends of the arms carrying the stitchers are yieldingly pressed toward one another by any suitable means, an interposed compression spring 35 being indicated as one form of such device.

30 One of the spinning roller shafts is arranged to be driven by a motor 36 mounted upon an extension 37 of the bracket 17, the motor shaft having a pinion 38 which meshes with a gear 39 on the shaft 26.

35 The operation of the device will be readily understood by those skilled in the art. The cord fabric is first stretched about the tread of the core, leaving the skirts or edges thereof free and unattached, as shown in Figure 3.

40 After the core has been given a preliminary whirl so as to set it in motion, the stitching wheels are brought into contact with the core and gradually fed inwardly. The working edges of the spinning rollers bear against 45 the fabric at the side of the core and drive the core through the medium of the fabric. The compression or forcing together of the cords is accomplished by the driving action described and which is illustrated in Figure

50 5, in which the direction of rotation of the driving stitcher wheel and the core are indicated by the arrows *a* and *b*. The movement of the cords is indicated by the small arrows *c*. It will be observed from this view

55 that when the fabric is out of contact with the stitcher and the core, the cords stand at their normal or partially separated positions.

The stitcher rollers, being of relatively large diameter, preferably from six to ten inches, 60 engage a considerable zone of fabric in advance of the point of contact of the fabric with the core and, because the speed of travel of the stitcher is slightly greater than the speed of travel of the portion of the tire carcass being operated upon, the elements of

the cord fabric, or other material from which the carcass is being built up, are gradually crowded together to progressively greater and greater degree along the contacting edge of the stitcher. The increased speed of the core and the increased fullness of the unapplied skirt of the fabric cause the fabric to fold back over the edge of the stitcher rollers at an increasing angle as the stitcher approaches the bead of the tire. The forward movement of the stitcher against the fabric at such increased angle somewhat increases the radial tension on the fabric to a desirable degree. In this way, the stitcher acts upon the cords to shift or crowd them together and, at the same time, to properly tension them and stick them to the side of the core or to the underlying fabric in their compacted or condensed condition. The flattening of the working edge of the stitcher, as shown in this view, although not essential, has been found to materially assist in securing the desired results. Stitcher rollers having their working faces formed of yielding or non-yielding material may be employed as desired.

It will be noted that the axis of the stitcher is located above the axis of the core, as shown by the line X of Figure 2. This is equivalent to placing the stitcher at an angle to the line of tangency and increases the dragging action upon the cords.

The stitcher carriage 14 is gradually fed inwardly toward the axis of the core 2 during the stitching operation by means of the 100 screw 15 so that the stitching rollers 27 travel in a spiral path over the surface of opposite sides of the core progressively approaching the inner edges thereof.

Furthermore, it is to be understood that the particular forms of apparatus shown and described, and the particular procedure set forth, are presented for purposes of explanation and illustration of the invention and that various modifications of said apparatus and procedure can be made without departing from my invention as defined in the appended claims.

What is claimed is:

1. In the process of manufacturing tires from cord fabric, the process of shaping fabric about a core which comprises stretching the fabric about the tread of the core, leaving the skirts of the fabric free and unattached to the core, the core being mounted 115 for free rotation, then applying the skirts of the fabric about the side of the core by exerting an inward pressure and a pull upon the fabric of the skirts transversely of the cords, the pull serving to crowd the cords together, apply them to the side of the core and rotate the core upon its axis, and progressively advancing the action toward the bead line in a spiral path.

2. Tire making apparatus comprising a 130

freely rotatable core, a roller movable toward the axis of the core and bearing against the side of the core with its edge against the core, and means to drive the roller, the roller rotating the core through the medium of the fabric to be applied thereto.

3. Tire making apparatus comprising a freely rotatable core, a roller having a yielding working surface which is pressed against the side of the core, and means to drive the roller and thereby rotate the core through the medium of the fabric between the roller and the core, the roller being movable toward the axis of the core.

15. 4. Tire making apparatus comprising a freely rotatable core, a disk-like roller having a yielding edge, means for forcing the roller against the side of the core, and means for driving the roller and advancing it toward the axis of the core and thereby rotating the core through the medium of the fabric between the roller and the core.

In testimony whereof I affix my signature.

HAROLD A. DENMIRE.
